UNITED STATES PATENT OFFICE.

WILLIAM H. LLOYD, OF CHICAGO, ILLINOIS, ASSIGNOR TO PYRAMID MANUFACTURING COMPANY, OF CHICAGO, ILLINOIS, A CORPORATION OF ILLINOIS.

WATER-CLOSET.

1,155,498.

Specification of Letters Patent.

Patented Oct. 5, 1915.

Application filed May 1, 1911. Serial No. 624,354.

To all whom it may concern:

Be it known that I, WILLIAM H. LLOYD, a citizen of the United States, and a resident of Chicago, county of Cook, and State of Illinois, have invented certain new and useful Improvements in Water-Closets, of which the following is a description, reference being had to the accompanying drawings, which form a part of my specification.

10 My invention relates to water closets of the type that project from a side wall or partition, as distinguished from the usual construction of closet which rests upon the floor.

15 My invention relates more especially to the means and method of fastening the closet bowl in place against the side wall or partition; the object being to provide means whereby the bowl may be readily secured in 20 place.

A further object of my invention is to so secure the bowl to the soil-pipe, that strains placed on the bowl will be transmitted to the soil-pipe instead of to the intervening wall, 25 and thus permit of a thin wall or partition being used intermediate of the bowl and the soil-pipe, as will more fully appear from the following detailed description.

In the drawings:—Figure 1 is a side elevation of a bowl secured in place with the portion constituting my invention being shown in vertical section. Fig. 2 is a plan view of the same, showing a horizontal section of the partition or wall. Fig. 3 is a 35 sectional view taken on the line 3—3 of Fig. 2 looking in the direction of the arrows. Fig. 4 is a side elevation of a bowl, with a modified form of my invention shown in vertical section. Fig. 5 is a plan view of the 40 same, and Fig. 6 is a sectional view taken on the line 6—6 of Fig. 5, looking in the direction of the arrows.

My invention is especially intended for use in connection with the wall type of 45 closet, the bowl A being supported entirely by the soil-pipe B; the bowl being so constructed as to leave the floor beneath the bowl free from any obstruction, thereby producing a much more sanitary condition.

50 The rear wall of the bowl is preferably formed without any protruding portions, so that it may be drawn up flush against the wall or partition C. In its preferred form,

the soil-pipe is provided with a hub or lateral connection a, the outer end of which 55 may be provided with a flare or flange, or it may be provided with a groove as at b into which the set-screws or bolts c are adapted to take. With this construction, in order to form the soil connection, a hub or band d is 60 screwed into or otherwise secured in the laterally extending hub or portion a of the soil-pipe. The outer end of this band d takes into the circumferential groove e surrounding the outlet opening of the bowl 65 where the style of the bowl as illustrated is employed; a water tight connection being formed by the washer or gasket f. Adapted to take about the hub a of the soil-pipe is a retaining ring or yoke D, which may be so 70 formed as to readily take about a short lateral connection and against the curved surface of the upwardly extending soil-pipe, as shown in Fig. 2. A suitable number of set-screws or bolts c are provided, which take 75 through the retaining ring or yoke and hold it in place.

In the construction shown in Figs. 1 to 3, the retaining ring or yoke D is provided with radially extending arms g, the ends of 80 which are provided with openings to receive the rods or bolts h, see Figs. 2 and 3. The arms g, are preferably provided at diametrically opposite points; and this retaining ring or yoke is so secured on the hub of the 85 soil-pipe as to have the arms extend out in horizontal direction, so that they may be in line with the horizontally extending passages in the sides of the bowl through which the securing rods or bolts h pass; the outer 90 ends of the securing rods or bolts h being provided with suitable heads, as shown in the drawings, to enable the rods h to be screwed into the arms g.

Instead of having the arms extend in the 95 manner shown and described, it is readily understood, of course, that the same may be made to extend in a different direction when a differently constructed bowl is employed. The retaining ring or yoke D is also shown 100 provided with the lugs or arms i, i and j. These lugs or arms are all provided with openings through which abutting or pressure distributing members, or bolts, k, k, and l, take; the ends of the members being 105 preferably provided with the enlarged abut-

ting ends or nuts, as clearly shown in Figs. 1 and 2. The lugs or arm *i*, *i*, are so arranged as to more evenly distribute the pressure or strains that may possibly be occasioned by any tendency of the yoke or retaining ring to tilt in a horizontal direction; while the lug or arm *j* is preferably provided at the lower central portion (if only one is employed) of the ring or yoke so that the bolt *l* may engage with the lower portion of the bowl, when the construction shown in Figs. 1 to 3 is employed. It will be seen in Fig. 1 that the bolts *k*, *k*, take against the rear side of the wall of partition C, while the bolt *l* takes through an opening in the wall and engages with the lower portion of the bowl.

It has been found sufficient to employ merely one bolt or pressure distributing device at the bottom side of the yoke; although with some constructions of bowls it may be preferable to provide the retaining member with more than one lug or arm *j*, so that any pressure of the bowl at the lower side may be taken care of.

In the installation of a closet bowl of the style illustrated and when the fastening means shown in Figs. 1 to 3 is employed, the yoke or retaining ring is slipped onto the hub or lateral connection of the soil-pipe and the set-screws *c* screwed down onto the hub or into the groove *b* with which the hub is provided; the pressure distributing devices or abutting bolts *k*, *k*, and *l* are then screwed into the lugs or arms *i*, and *j* of the retaining yoke; the pressure distributing bolts or member *k*, *k*, being screwed into the yoke so as to take tightly against the wall or partition and thereby hold the retaining ring or yoke in a perpendicular position and prevent any tendency on its part to tilt forward; while the pressure distributing member or bolt *l* is screwed into the lug or arm *j* so as to have its one end extend through the wall and flush against the lower end of the bowl where the nut is secured at the end of the bolt as shown. Instead of having the abutting member or nut at the end of the bolt, when desired, the bolt may take through the abutting nut and be made to engage with the bowl; the nut, of course, being screwed upon the rod or bolt so as to come up flush against the bowl or wall, as desired. The band *d* having been screwed into the hub *a* of the soil-pipe or otherwise secured thereto, the gasket *f* is put into place after which the bowl may be fastened up by the retaining rods or bolts *h*. By screwing the bolts or rods *h* into the arms *g* to a sufficient extent, the bowl will be drawn up tightly against the wall or partition and the gasket *f* will be firmly incased and compressed between the lateral connection of the soil-pipe and the reduced portion *e* in the rear wall of the bowl.

With my improved construction, it will be seen that it is necessary to employ but one gasket to effect a water-tight joint between the bowl and the soil-pipe, owing to the simplicity of the construction.

It is apparent that in a closet of this type, where the bowl is secured against the wall or partition by being connected with the soil-pipe, that when a weight is placed on the bowl, unless proper methods are employed, the tendency of the bowl would be to sag or bear against the wall beneath the point of fastening. Where the wall is thin, or the partition consists of a marble slab, it is quite important that the method or means of securing the bowl in place be such that this tendency of the bowl to sag is obviated and that the strain or weight, instead of being against the thin wall or partition, be transmitted to the soil-pipe connection, and thereby prevent any possibility of the thin wall or slab becoming cracked or broken.

By the use of my improvement, it is apparent that the entire strain or weight is taken off of the wall or thin partition C and transmitted to the soil pipe.

In Figs. 4, 5, and 6, I have shown a modified form of my invention, wherein the use of a separate retaining ring or yoke is obviated, and the bolt or rod-receiving portion 95 is formed integral with the soil-pipe B. When this construction is employed, the securing bolts *c* are not needed. In Fig. 6, I have also illustrated a different manner of having the lugs or arms *i*', *i*', project.

It is, of course, understood that where the side wall is of sufficient thickness and strength, the abutting member or members *l* may simply be so adjusted as to take against the rear side of the partition or wall instead 107 of taking through the wall and against the rear surface of the bowl.

It is essential in closets of this description that the connections or method of fastening be as firm as possible so as not only to relieve the wall or partition of as much strain as possible, but also to keep the bowl in a horizontal position and thereby prevent the possibility of any leaks between the outlet or discharge opening of the bowl and the 115 soil-pipe connection.

Instead of having the lug or lugs *j* extend in the vertical direction as shown, it will be understood, of course, that the same may be made to extend in a lateral direction, and 120 preferably to either side of the median line of the soil-pipe.

In the drawings I have shown the member or bolt *l* extending through the lower part of the yoke or lug *j* and in proximity with the soil-pipe. It is apparent that the member *l* may be provided at this end with a nut or screw-cap, similar to the nut shown at the opposite end where it takes against the lower part of the bowl, so that the nut 130

or cap may be screwed up on rod 7 until it abuts against the soil-pipe, and thereby prevent any possible tilting of the yoke.

I have shown and described what I believe to be the simplest construction of my invention, but it is apparent that a number of alterations may be made in certain details without departing from the spirit of my invention, and I do not wish to be understood as limiting myself to the exact construction shown and described, but

What I do claim and wish to secure by Letters Patent is:—

1. In a water closet, the combination of a soil-pipe provided with a lateral connection, a bowl having a discharge-opening in the rear face thereof, said bowl taking up flush against a side wall or partition, with retaining means located on the lateral connection of the soil-pipe, mechanism whereby the bowl is secured to said means, and pressure devices whereby the pressure of the bowl is transmitted to said means.

2. The combination of a bowl having a vertical rear face provided with a discharge opening and taking against a side wall or partition, and a soil-pipe located on the opposite side of the wall or partition, with means for securing the bowl in place against the wall or partition, and adjustable means adapted to engage the rear face of the bowl adjacent the lower end thereof for relieving the wall of the lateral pressure of the bowl.

3. In a water closet, the combination of a soil-pipe provided with a lateral connection, a bowl provided with a discharge opening in the rear face thereof, means whereby the bowl is secured to said lateral connection, and adjustable abutting members whereby the pressure of the bowl is transmitted to the soil-pipe.

4. In a water closet, the combination of a bowl having a discharge-opening in the rear face thereof, said bowl being provided with a vertical rear face taking up flush against a side wall or partition, a soil-pipe, and retaining means secured to the soil-pipe, with means extending through the bowl and engaging with said first mentioned means for securing the bowl in place, and adjustable means arranged in engagement with the rear face of the bowl at a point beneath the discharge-opening thereof for receiving the lateral pressure of the bowl.

5. A water closet of the class described, comprising a bowl fitting against a side wall or partition, a soil-pipe provided with a lateral connection, means arranged to fit about said connection whereby the bowl is removably held against a side wall, and mechanism engaging with said means and adapted to abut against the bowl to transmit the pressure of the bowl to the soil-pipe.

6. In a water closet of the class described, a soil-pipe provided with a lateral connec-

tion, means adapted to take about the lateral connection and to secure the bowl against a side wall, and devices adjustably secured to said means and adapted to take against the rear face of the bowl whereby the pressure of the bowl is transmitted to the soil-pipe.

7. In a water closet of the class described, means secured to the soil-pipe whereby the bowl is removably held against a side wall, and mechanism adjustably secured to said means and arranged to take against the rear side of the wall and rear face of the bowl.

8. In combination with a soil-pipe provided with a lateral connection, a yoke surrounding and removably secured to said connection, a closet bowl secured to and supported laterally by said yoke and having a discharge passage communicating with said connection, and means engaging with said yoke and adapted to fit against the rear face of the bowl whereby the pressure is transmitted to the lateral connection.

9. In combination with a water closet bowl having a laterally extending discharge opening in its rear face, a soil-pipe provided with a lateral connection located on the opposite side of a wall, means adapted to take about said soil-pipe connection and to hold the bowl against the side wall, and pressure devices adjustably secured to said means and arranged to take against the rear side of the wall and rear face of the bowl.

10. The combination of a water closet bowl having a laterally extending discharge opening in its rear face, a soil-pipe located on the opposite side of a wall or partition and provided with a lateral connection to register with said discharge opening in the bowl, a yoke adapted to take about said lateral connection, means whereby the bowl is removably held against the wall or partition and supported by said yoke, with devices adjustably secured to said yoke and adapted to take against the rear side of the wall or partition and the rear face of the bowl whereby the strains on the bowl are transmitted to the soil-pipe.

11. In a water closet of the class described, the combination of a bowl having a discharge opening in the rear face thereof, said bowl being provided with a vertical rear face adapted to take up flush against a side wall or partition, with a soil pipe, retaining means secured to the pipe and extending to either side of the median line of the pipe, mechanism whereby the bowl is secured to said means, and devices adjustably secured to said means whereby the pressure on the bowl is transmitted to the pipe.

12. In a water closet of the class described, the combination of a soil-pipe provided with a lateral connection, a closet bowl provided with a flat surface on its rear side adapted to take against a side wall or

- partition, said bowl being provided with a discharge opening in its rear side, means whereby a tight joint between the lateral connection and the discharge opening is formed, with means for removably securing the bowl to the soil-pipe and against the wall or partition and permitting of lateral adjustment, and adjustable means arranged above and below the first mentioned means adapted to take the lateral pressure of the bowl off the wall or partition.
13. In a water closet of the class described, the combination of a soil-pipe, a closet bowl provided with a flat rear face to adapt it to take against a wall or partition, said bowl being provided with a discharge opening in its rear face, means for forming a water tight joint between the bowl and the soil-pipe, with means whereby the bowl is removably secured to the soil-pipe and against the wall or partition, and mechanism intermediate of said last mentioned means and the lower end of the bowl whereby the pressure of the bowl is transmitted through said mechanism to the soil-pipe.
14. In a water closet of the class described, the combination of a soil-pipe with a bowl provided with a vertical rear face adapted to take against a side wall or partition and having a discharge opening in the rear face, and means for removably securing the bowl to the soil-pipe and against the wall or partition, a portion of said means being adjustable and arranged to take against the lower edge of the bowl and transmit any pressure on the bowl to the soil-pipe.
15. In a water closet, the combination of a soil-pipe, a bowl provided with a vertical rear face adapted to take up flush against a side wall or partition, means whereby the bowl is secured to said soil-pipe, with adjustable members disposed radially in planes above and below the plane of said means.
16. In a water closet of the class described, a soil-pipe, a bowl provided with a vertical rear face adapted to take against a partition or side wall, means whereby the bowl is suspended from the soil-pipe and held against the wall or partition, and adjustable mechanism disposed circumferentially intermediate of the bowl and pipe whereby the rear face of the bowl may be held flush against the wall or partition with the strains on the bowl transmitted to the soil-pipe.
17. In a water closet of the class described, a soil-pipe, a bowl provided with a vertical rear face adapted to take against a partition or side wall and having a discharge opening in the rear face, means whereby the bowl is suspended from the soil-pipe and removably held against the wall or partition, and mechanism adjustably secured to said means and adapted to take through the wall or partition against the rear face of the bowl whereby the wall or partition is relieved of the weight or strains on the bowl.
18. A water closet of the class described, comprising a bowl provided with a vertical rear face adapted to take up flush against a side wall or partition, means for removably securing the bowl against the side wall or partition, and adjustable mechanism arranged in a different horizontal plane from said means adapted to receive the lateral thrusts of the bowl without transmitting the same to the side wall or partition.
19. The combination of a bowl adapted to be suspended against a side wall or partition and provided with a discharge-opening in its rear face, a soil-pipe provided with a laterally disposed portion, and a discharge connection secured in said lateral portion and extending through the wall or partition and communicating with the discharge-opening in said bowl, with means connected with the bowl and said pipe for securing the bowl in place, and adjustable means located exteriorly of the soil-pipe and adapted to engage with the bowl and the pipe for receiving the lateral pressure of the bowl.
20. Bowl sustaining means comprising a member adapted to be secured to a support, said member being provided with a downwardly projecting arm, and means intermediate of the member and its downwardly projecting arm and the bowl whereby the relative position of the support and the bowl will be maintained and strains on the bowl transmitted to said member.
21. The combination of a bowl having a vertical rear face adapted to fit up flush against a side wall or partition and provided with a discharge-opening in said face, and a soil-pipe, with a member arranged intermediate of the bowl and the soil-pipe and provided with a series of radially disposed arms, means extending through the bowl and some of said arms for securing the bowl in place, and means arranged intermediate of the other arms of said member and the bowl whereby tilting movement of the bowl will be prevented.
22. In apparatus of the class described, the combination of a soil-pipe connection or hub having a laterally disposed portion provided with a series of arms integral therewith, some of said arms being disposed laterally beyond the median line of the hub or lateral connection while the other arm is disposed vertically and substantially parallel with the median line of said connection or hub, a bowl provided with a vertical rear face having a discharge opening adapted to register with said lateral connection or hub, with members secured to the bowl and a portion of the laterally disposed arms for securing the bowl in place, and adjustable

means engaging with the bowl and with some of said laterally disposed arms and with the vertically disposed arm whereby tilting movement of the bowl will be prevented and lateral pressure of the bowl transmitted to said lateral connection or hub.

23. In apparatus of the class described, the combination of a soil-pipe connection or hub having a laterally disposed portion provided with a series of integral arms, a portion of said series being disposed laterally while the other portion is disposed vertically, a bowl provided with a vertical rear face having a discharge opening adapted to register with the laterally disposed portion of the soil-pipe connection or hub, and members secured to the bowl and to said laterally disposed portion of said series of arms for securing the bowl in place, with means adapted to engage with the bowl and the vertically disposed portion of said series of arms whereby lateral pressure of the bowl will be transmitted to said soil-pipe connection or hub.

24. In a water closet, the combination of a soil-pipe provided with a lateral connection, a bowl having a discharge opening in its rear face adapted to register with said lateral connection and take up flush against a side wall or partition, with means located rearward of the side wall or partition and having connection with the bowl whereby the latter is secured in place, and mechanism located beneath the lateral connection and discharge-opening adapted to prevent tilting movement of the bowl and to receive the lateral pressure of the bowl.

25. In combination with a soil-pipe having a lateral connection, a bowl provided with a vertical rear face adapted to fit up flush against the side wall or partition and provided with a discharge opening in said face, a ring surrounding and secured to said lateral connection and provided with radially disposed extensions, bolts secured in a portion of said extensions and in the bowl whereby the latter is secured to the lateral connection, and adjustable members secured to the other portion of said extensions whereby strains on the wall or partition are distributed, the relative position of the ring to the wall or partition maintained, and pressure on the bowl transmitted to the soil-pipe.

26. In a water closet, the combination of a soil-pipe having a lateral connection provided with a flanged end, a yoke adapted to

fit onto said lateral connection, means secured to the yoke and arranged to engage with the flange on the end of said lateral connection whereby the yoke is removably held in place, said yoke being provided with a series of radially arranged extensions, a bowl having a vertical rear face provided with a discharge opening therein, and rods engaging with the bowl and with a portion of said series of radial extensions for securing the bowl against a side wall or partition, with means arranged above and below said rods and adjustably secured to the other portion of said series of extensions whereby the relative position of the bowl to the wall is maintained and strains transmitted through the yoke to the soil-pipe.

27. In apparatus of the class described, the combination of a support located rearward of a side wall or partition, a bowl provided with a vertical rear face adapted to take up flush against the other side of the wall or partition, means whereby the bowl is secured against the side wall or partition, and adjustable means adapted to engage with the bowl and the support for preventing tilting movement of the bowl, said first mentioned means and the adjustable means being disposed in different horizontal planes.

28. In apparatus of the class described, the combination of a support located rearward of a side wall or partition, a bowl provided with a vertical rear face adapted to take up flush against the other side of the wall or partition, means whereby the bowl is secured against the side wall partition, and adjustable means adapted to engage with the bowl and the support at a point beneath said first mentioned means for preventing tilting movement of the bowl.

29. In a water closet, the combination of a support located rearward of a side wall or partition, a bowl provided with a vertical rear face adapted to fit up flush against the front side of a wall or partition and provided with a discharge-opening, means for effecting a water-tight connection with said discharge-opening, and means whereby the bowl is secured to said support and against the wall or partition, with means engaging with the bowl and the support and adapted to be adjusted so as to transmit pressure from the bowl to the support without affecting the water-tight connection.
